UNITED STATES PATENT OFFICE.

ARTHUR ABRAHAM LUND, OF SUSANVILLE, CALIFORNIA.

LUMBER-PILE BAR.

Application filed March 28, 1927. Serial No. 179,164.

The invention has for its object to provide a new and improved lumber piling bar, for piling or stacking lumber with ease and facility and in a manner preventing marring 5 and degrading of the lumber.

In its more detailed nature the invention seeks to provide a device of the character stated which includes a supporting member readily mounted upon to be supported by a 10 part of the lumber being piled, and a swivelly mounted rest head upon which a piece of lumber being piled is rested during the piling operation, said head having means to so engage the lumber as to prevent slipping and yet not mar the same, and spring 15 and weight balance features to always return said rest head to a desired normal position when not supporting lumber.

With the above and other objects in view 20 that will hereinafter appear, the invention still further resides in the novel details of construction, combination and arrangement of parts, all of which will be first fully described, then be particularly pointed out in 25 the appended claims, reference being had to the accompanying drawings, in which:

Figure 1 is a perspective view illustrating the invention in use.

Figure 2 is a side elevation of the invention.

Figure 3 is an inverted plan view.

Figure 4 is an end view.

Figure 5 is a detail perspective view of the rest head per se.

Figure 6 is a detail perspective view of the 35 bifurcated swivel head.

Figure 7 is a detail perspective view of the retainer and stop cup.

Figure 8 is a detail perspective view of the return spring.

In the drawings, in which like numerals of reference indicate like parts in all of the figures, 1 is a support bar which is preferably constructed of a flat bar of metal and has one end thereof wedge sharpened as at 2 to provide 40 penetrating prongs for facilitating insertion of the said end between the boards of a pile to mount the said bar somewhat in the manner illustrated in Figure 1 of the drawings. To prevent inadvertent displacement of the 45 bar when so mounted the wedge shaped end thereof is provided at its top surface, with upwardly projecting prongs or barbs 3, sort of saw-tooth in shape, and directed in such manner that they will not appreciably hinder 50 insertion of the bar end between boards of a pile but any tendency toward inadvertent

withdrawal of the said bar will be thwarted by the said teeth 3 biting into the surface of the board engaged thereby.

The other end of the bar is twisted as at 60 4 to present the flat surfaces thereof in a vertical plane or at right angles to those of the portion 1 hereinbefore mentioned and is equipped with an enlarged bearing head 5 having a vertical central bore 6 therethrough 65 to receive the shank 7 depending from the bifurcated swivel mounting member 8 and provide a rotatable bearing therefor.

When the member 8 is mounted in and upon the bearing head 5 a bearing washer 9 is 70 interposed between the said parts and a retainer and stop cup 10 is pin-secured as at 11 to the lower end of the shank 7 to secure the said member 8 to position while permitting a degree of rotative movement thereof 75 for a purpose later to be described.

The cup member 10 is provided with an upstanding flange 12 having a portion thereof removed to provide an opening to permit rotative movement of the cup relatively to 80 the end 4 of the support bar 1 and stop shoulders 13 defining the said opening and adapted to engage the said bar end to limit the said movement. The upstanding flange provides a hollow portion to accommodate the mounting 85 of a coil spring 15, one end of which is secured in the cup as at 16 and the other end of which may be secured as at 17 to the bar portion 4 to serve to retain the cup and the mounting member 8 carried thereby in the 90 normal position hereinafter described, and to return the same to said normal position after being moved for purposes also later described.

The ears of the bifurcated head 8 are apertured to receive a bearing pin 18 upon which is horizontally rotatably mounted the rest head 19 which is cored out as at 20 to so balance the said head upon its rotatable mounting that it will normally rest in the 100 position illustrated in Figure 4 of the drawings with its flat or lumber engaging face on a vertical plane parallel that on which the flat sides of the bar portion 40 are presented or, in other words, in a plane normal to the 105 face of the lumber pile into which the mounting bar 1 is inserted.

The lumber engaging face of the head 19 is provided with a plurality of parallel equidistantly spaced grooves 21 in which are inserted a plurality of anti-slip teeth 22 which are substantially saw tooth in shape and 110

those of alternate rows of which are directed in opposite directions in the manner shown in Figure 5 of the drawings. Thus, the said teeth overcome any tendency of a board slipping off the rest head in any direction.

The use of my improved piling bar will be readily understood to those skilled in the art and is clearly illustrated in Figure 1 of the drawings from which it will be observed that, 10 in order to pile boards from the ground onto a pile of boards, or from a lower pile of boards onto a higher pile, it is only necessary to elevate an end of the board so as to raise the same upon the rest head 19 in a substantially balanced manner, when the board may be turned, 15 using the rest head, in its horizontally rotatable manner, and its swivel mounting in the bearing head 5, to facilitate the necessary rotative movement to bring the elevated 20 end thereof up onto the top of the lumber being piled when it is an easy matter to slide the board up to its desired place upon the pile. The cut out portion of the cup 10 will permit the necessary rotation to accomplish 25 the movement just described and, immediately upon removal of the board from its supported position upon the rest head 19, the spring 15 will act to return the rest head and its mounting devices to the normal position 30 illustrated in Figures 2, 3 and 4 of the drawings.

From the foregoing description, taken in connection with the accompanying drawings, 35 it is thought the novel details of construction, the manner of use and the advantages of my invention will be readily apparent to those skilled in the art to which it relates.

What I claim is:

1. A device of the class described, comprising 40 a substantially horizontal supporting bar, having an end adapted to be inserted into a lumber pile to cause said bar to project horizontally from said pile, means to hold said bar against shifting in the pile, and a rest head mounted on said bar by a universal connection.

2. A device of the class described comprising 45 a supporting bar adapted to have one end inserted into to be supported by a lumber pile, a rest head swivelly mounted at the other end of said bar, said inserted bar end being flatwise bevel-sharpened to form an entering wedge, and teeth projecting from the bar adjacent its inserted end to bite into the lumber of the pile and prevent inadvertent displacement of said inserted end.

3. A device of the class described comprising 50 a supporting bar adapted to have one end inserted into to be supported by a lumber pile, a rest head swivelly mounted at the other end of said bar, said inserted bar end being flatwise bevel-sharpened to form an entering wedge, and teeth projecting from the bar adjacent its inserted end to bite into the lumber of the pile and prevent inadvert-

ent displacement of said inserted end, said teeth being inclined in a manner facilitating insertion of said inserted end but to thwart inadvertent withdrawal.

4. A device of the class described comprising 70 a supporting bar adapted to have one end inserted into to be supported by a lumber pile, a rest head swivelly mounted at the other end of said bar, said head being horizontally pivotally mounted on said swivel mounting, and weight-balanced to cause it normally to rest with its lumber engaging face vertical.

5. A device of the class described comprising 75 a supporting bar adapted to have one end inserted into to be supported by a lumber pile, a rest head swivelly mounted at the other end of said bar, said head being horizontally pivotally mounted on said swivel mounting, weight-balanced to cause it normally to rest with its lumber engaging face vertical, and 80 anti-slipping teeth projecting in alternate directions from the lumber engaging face of said rest head.

6. A device of the class described comprising 85 a supporting bar adapted to have one end inserted into to be supported by a lumber pile, a rest head swivelly mounted at the other end of said bar, said head being horizontally pivotally mounted on said swivel mounting, weight-balanced to cause it normally to rest with its lumber engaging face vertical, and means including a spring to 90 normally hold the rest head swivel mounting to present the rest head lumber engaging face on a plane normal to the face of the lumber pile which supports the device.

7. A device of the class described comprising, 95 a flat bar having one end insertable into a pile of lumber to form a support and having its other end twisted to present its flat faces vertically and equipped with an enlarged bearing head having a vertical bore therethrough, a bifurcated swivel mounting member having a depending shank projecting through the bearing head bore to swivelly mount said member, a retainer and stop cup secured on the projected end of said shank to secure the swivel mounting member and having means to limit the swivel mounting movement, and a rest head carried 100 in the bifurcation of the swivel mounting member.

8. A device of the class described comprising 110 a flat bar having one end insertable into a pile of lumber to form a support and having its other end twisted to present its flat face vertically and equipped with an enlarged bearing head having a vertical bore therethrough, a bifurcated swivel mounting member having a depending shank projecting through the bearing head bore to swivelly mount said member, a retainer and stop cup secured on the projected end of said shank to secure the swivel mounting member and having means to limit the swivel mount- 115

ing movement, and a rest head carried in the bifurcation of the swivel mounting member, and a coil spring coiled about the shank in the cup and having one end connected to the 5 cup and its other end connected to the bar and serving normally to hold the swivel mounting member in one position.

9. A device of the class described comprising, a bearing member equipped with an enlarged bearing head having a vertical bore therethrough, a bifurcated swivel mounting member having a depending shank projecting through the bearing head bore to swivel- 10

ly mount said member, a retainer and stop cup secured on the projected end of said shank to secure the swivel mounting member and having means to limit the swivel mounting movement, a rest head carried in the bifurcation of the swivel mounting member, and a coil spring coiled about the shank in 15 the cup and having one end connected to the cup and its other end connected to the bar and serving normally to hold the swivel mounting member in one position.

ARTHUR ABRAHAM LUND.
